Patented July 12, 1927.

UNITED STATES PATENT OFFICE.

JOHN W. HUDSON, OF LYNBROOK, NEW YORK.

COOLING MECHANISM FOR INTERNAL-COMBUSTION ENGINES.

Application filed October 16, 1920, Serial No. 417,297. Renewed December 4, 1926.

This invention relates to cooling mechanism for single and multiple cylinder combustion engines and particularly to engines of the air cooled type.

In engines of the air-cooled type it is quite impossible to satisfactorily cool the engine at and about the exhaust valves and it is a primary object of my invention to provide means which will operate by induced suction to draw off the waste heat and to create a circulation of atmospheric air around the valves in time with the order of their operation.

My invention is directed more particularly to aeroplane motors and I have provided an induction device which is adapted to be placed in an air lane or exposed to atmospheric air to serve as a collector of such air, the device being coupled with the exhaust manifold and the latter arranged in communication with the stem guide of an exhaust valve so air passing into the induction device will serve to create suction therein with a resulting tendency toward a forced expulsion of the exhaust gas and heat from the cylinder of an internal combustion engine and from around the exhaust valve.

In order to best accomplish this object I have provided in combination with my induction device above referred to, a valve wherein is included a means which operates in time with the movements of the valve to admit atmospheric air to be drawn into the exhaust manifold and around the valve so that the latter is maintained in a cool state at practically all times.

Another object of the invention is to provide a mechanism which will serve to increase the efficiency of an internal combustion engine by incorporating an induction device in the exhaust line of the engine, the device being also designed whereby it constitutes an efficient form of muffler without creating back pressure as is usually encountered from the use of various forms of mufflers.

With the above and other objects in view which will appear as the nature of the invention is better understood, the same consists in the improved construction and novel arrangements of parts which will hereinafter be fully described and particularly pointed out in the claims.

In the accompanying drawing, has been illustrated, a single and preferred form of the invention, it being, however, understood

that no limitations are necessarily made to the precise structural details therein exhibited, but that changes, alterations and modifications within the scope of the claims 60 may be resorted to when desired.

The view is a vertical section through a part of the cylinder of an internal combustion engine showing the application of my invention thereto.

In carrying the invention into practice, use is made of an induction device 5 which is substantially of conical formation and provided with a flared mouth 6 at its large intake end, the walls 7 of the mouth being 70 restricted in the direction of the flared end 8 of the throat 9 of said device 5. The diameter of the throat 9 increases forwardly and rearwardly respectively from a line drawn vertically through said throat and as 75 illustrated the walls of said throat are spaced at their forward ends from said walls 7 so as to provide an intervening orifice 10 therebetween. This orifice is in open communication with a surrounding chamber 80 11 which extends preferably for the full length of the said throat and the same is in communication with an exhaust manifold 12. The rear or restricted end of the said induction device 5 is provided with one or a 85 suitable number of discharge orifices 13.

A, conventionally illustrates a portion of the cylinder of an internal combustion engine and B, the valve of such engine. The said valve is arranged in a casing or chamber C which includes an integral valve stem guide D and a cylindrical cooling member E. The said cooling member is arranged with its walls in spaced relation to the walls of the guide D so that an air circulating 90 space F is formed between such parts. The stem G of the valve B is adapted to be actuated by means of a rocker H of any suitable well known construction. Carried by the stem G is a valve cap I which operates 100 over the outer end of the cylindrical member E so that when the valve B is closed against its seat, the passage way F will be in open communication with the outside atmosphere. In other words, when the valve 105 B is closed, the valve cap I is lifted from the said member E so as to uncover the outer end of the said passage way F. The opposite end of the said passage way F is in communication with the exhaust manifold 12 110 by means of a lateral connection J which is secured at K to one end of said manifold.

The induction device 5 may be positioned immediately adjacent to the cylinder A or can be extended to any point therefrom where the intake end 6 of the device will be 5 operatively arranged for the reception of a draft or current of atmospheric air. As the air enters the mouth 6 and discharges therefrom into the throat 9, suction is induced at the orifice 10 and in the exhaust manifold 10 and also in the space F around the valve stem guide D. As the valve B is moved in the ordinary working of the engine, a constant suction is created in the exhaust manifold and atmospheric air is permitted 15 to be drawn into the space F in proper time with the closing of said valve B against its seat. In this manner the exhaust manifold of the engine is provided with means for augmenting or accelerating the discharge of 20 the exhaust gas and heat therefrom and fresh supplies of atmospheric air are permitted to enter the engine in proximity to the exhaust valve so as to retain the same in a comparatively cool state at all times. It will be understood that after the air passes from the throat 9 of the induction device 5 it is free to leave the device by way of the mentioned orifice 13.

While I have stated use of the invention 30 in connection with an exhaust valve, it is desired that the valve be simply illustrative of a mechanism constituting part of an internal combustion engine and that the invention can be satisfactorily used in combination with any other part of an engine where a cooling by the same or similar atmospheric process may lend toward efficiency 35 in the operation of an engine.

What is claimed as new is:—

40 1. The combination with an internal combustion engine including its exhaust manifold and exhaust valve and means for controlling movements of the latter, of a guide member for the stem of the exhaust valve, said guide member having a portion inte-

rior of the manifold and a portion exterior of the manifold, the said guide member having an air space opening at one end on to the exterior portion of the member and at its opposite end on to the interior portion thereof, a valve carried by the aforesaid exhaust valve and movable therewith and with respect to the exterior portion of the guide member so as to respectively cover and uncover said space in movements of the exhaust valve, and means for inducing suction in said manifold, said means comprising a hollow member having an intake end and an exhaust end, a throat section arranged in said member, the walls of the 60 throat section at one end of the latter extending directly against the walls of said hollow member in sealed engagement therewith, the walls of the throat section at the opposite end thereof being in communication 65 with said intake, and an opening between the ends of said hollow member for communication with the exhaust manifold.

2. The combination with an internal combustion engine including its exhaust manifold and exhaust valve and means for controlling movements of the latter, of a guide member for the stem of the exhaust valve, said guide member having a portion interior of the manifold and a portion exterior 75 of the manifold, the said guide member having an air space opening at one end on to the exterior portion of the member and at its opposite end on to the interior portion thereof, a valve carried by the aforesaid exhaust valve and movable therewith and with respect to the exterior portion of the guide member so as to respectively cover and uncover said space in movements of the exhaust valve, and means for inducing suc- 80 tion in said manifold.

In testimony whereof I have affixed my signature.

JOHN W. HUDSON.
